PORTABLE INCINERATOR

Milan O. Nelson, Petaluma, Calif.

Application October 8, 1956, Serial No. 43,259

Term of patent 7 years

(Cl. D81—1)

The figure is a front perspective view of a portable incinerator showing my new design, the opposite side thereof being the same in appearance as the side shown.

The back of the incinerator is plain and the bottom is open.

I claim:

The ornamental design for a portable incinerator, as shown and described.
